UNITED STATES PATENT OFFICE

ALBERT R. LEWELLEN, OF DETROIT, MICHIGAN, ASSIGNOR TO GENERAL MOTORS CORPORATION, OF DETROIT, MICHIGAN, A CORPORATION OF DELAWARE

HEAD LAMP

Application filed January 16, 1930. Serial No. 421,176.

It is the object of this invention to provide a head-lamp organization with simple, inexpensive and reliable means for centering and securing the main parts thereof in assembled relationship; and preferred embodiments of the invention may involve the use, within an external plate-retaining rim element, which may be C-shaped in radial section, of a tension band that serves to retain said rim by constrictive engagement with parts interior thereto.

The invention preferably includes externally accessible means for so tensioning said band as to bring a flange or bead thereon into a resilient retaining engagement with a cooperating part upon one of the main concave elements of the head-lamp; and said concave elements preferably include not only mutually engaging integral flanges, disposed at an angle to one another, but also integral extensions, disposed at right angles to one another, upon said flanges,—the flanges and/or extensions serving to centre the mentioned parts and also to effect a bayonet joint interconnection therebetween.

This invention, in some embodiments thereof, contemplates the use of strip stock in the production of said rim. It also contemplates the use of a novel inwardly-extending interlocking element or elements, preferably hook-like in form, interiorly and permanently secured to said rim; and, if desired, one of the elements last referred to may include a plate which serves to unite the ends of said strip stock to form said rim,—incidentally providing an opening for the reception of angle elements, or the like, if provided upon or secured to the ends of the mentioned band, to receive a suitable tensioning screw.

Other objects of this invention may be best appreciated from the following description of illustrative embodiments thereof, taken in connection with the appended claims and the accompanying drawing:

Figure 1 is a front elevational view,—serving to show how Figures 2 and 3 are taken.

Figure 2 is a substantially radial detail view, taken somewhat as suggested by the line 2—2 of Figure 1, but on a larger scale.

Figure 3 is a view comparable with Figure 2 but taken substantially as indicated by the line 3—3 of Figure 1.

Figure 4 is a detail sectional view, with a slight perspective effect, taken substantially as indicated by the line 4—4 of Figure 3.

Figure 5 is a side elevational view, taken substantially as indicated by the arrow 5 of Figure 1, with parts broken away to a substantially median plane,—some features of modification being suggested in this figure.

Referring first to conventional features included in the illustrated embodiment, a main concave shell element 11 is shown as interiorly receiving a concave reflecting element 12,—the latter being so spaced from the former as to provide for the positioning of socket elements 13, 14 and 15 with twin-wire conductive elements 16, 17 and 18 therebetween; an annular rim 19 is shown as including an inwardly extending and slightly resilient flange 20 for the retention of a light-transmitting plate 21, of any preferred character, and as engaging the outer concave element 11; and the entire organization referred to may be supported by means such as a usual bracket 22,—retaining the head of a screw 23 in such manner as to permit adjustment of the headlamp to any desired position relatively to some substantial structural element, not shown. The concave reflecting element 12 is shown as provided, near the periphery thereof, with an annular bead 24, disposed favorably to engagement by a felt or other gasket or cushioning element 25,—against which a flange 26 on the plate 21 is pressed by the mentioned flange 20; and the present invention relates, as indicated above, more particularly to expedients for centering and retaining the mentioned parts in their assembled relationship.

Adjacent to the mentioned bead 24, the inner concave element 12 is shown as provided with a substantially cylindrical rearwardly bent flange 27, seated against a substantially flat and inwardly bent flange 28, provided upon the outer concave element 11. The latter element is shown as provided

100

with a substantially cylindrical extension 29, with which the mentioned cylindrical flange 27 is in external engagement; and the last-mentioned flange may advantageously be 5 provided with a flat radial extension 30, lying substantially parallel with the mentioned flange 28.

To assure inwardly application of pressure through mentioned parts including the 10 conical flange 20, and to provide for the retention of the rim 19 in a preferred position, the latter may interiorly receive a tension band 31. This is shown as shaped to 15 interfit between the gasket 25 and an additional flange 32,—provided upon the rim 19 adjacent one of a plurality of beads 33 and 34, peripherally formed upon the outer concave element 11. The tension band 31 is shown as provided with a bead 35, intermediate 20 the width thereof, adapted to so engage the mentioned bead 34, upon constriction of said band, as to hold the rim 19 in its illustrated position; and tension may be applied to said band by means of a screw 25 36. This screw is shown as extending through openings in a pair of brackets 37, 37', secured to terminal portions of the band 31, and extending through an opening in the rim 19; and, for an interlocking effect, preventing 30 undesired relative rotation of mentioned parts, the respective flanges 26 and 28, and also the extension 30 upon flange 27, may be provided with suitable coincident openings,—such as slots 38, 38' and shown in 35 the flanges 26 and 28; and an interlocking effect may then be obtained by the insertion therethrough of a pin or a suitable hook-like or inwardly curved element 39. This may be secured to the rim 19, as by means 40 of rivets 40; and a plate-like portion of the element 39, through which the mentioned rivets extend, may serve to unite the ends of the rim 19, if the latter is formed from strip stock, and also to provide an opening 41, 45 through which the brackets 37, 37' may extend.

Although the foregoing clamping arrangement serves to hold the reflector 12 to the shell 11, it is desirable in some instances to 50 provide an additional means to positively secure the reflector and shell together. For this purpose, the flange 27 may, for example, be provided not only with the mentioned flat or radial stop extension 30 but with additional integral extensions in the form of cam hooks 42,—shown as disposed in the plane of flange 27 and adapted (as may best be seen in Figures 3 and 4) to effect a bayonet-joint connection between mentioned 55 flanges by entering through suitable slots or openings 43 in flange 28,—effecting an interior engagement thereof upon a slight relative rotation, in a known manner.

In Figure 5, it is incidentally suggested 60 that a plug 13' and the socket 13 be secured

together by means involving the provision of an L-shaped cut 44 in the socket element 13 and the provision of a boss or projection 45 upon an interposed metallic shell 46,—said shell being preferably crimped onto said 70 plug, as at 47; but, in preference to providing a usual bayonet-joint by the means last referred to, a somewhat trapezoidal flap formed by the mentioned cut is preferably 75 momentarily bent outward, along a line such as that suggested at 48, during the insertion of said plug and the positioning of said projection,—this construction being such as to obviate risk of subsequent accidental separation of the relatively inaccessible parts referred to.

Figure 5, assuming the rim 19a to have been seamlessly formed from sheet stock, shows an interlocking element 39a as including no connection plate; and the cross-sectional outlines of terminal elements 37a, 37a' of band 31a correspond with the usage of an early embodiment of the present invention. A bulb 49, replaceably secured in socket 14, may include two filaments 50 and 50',— 90 the former being at or very near a focus of the reflector 12, which may be almost parabolic; and a bulb 51, very eccentrically positioned, may be of a comparatively low candle power suitable to a parking light. It 95 will, however, be understood that the last mentioned features, herein referred to for the sake of completeness, are but remotely related to the centering and securing devices to whose protection the present application 100 is primarily directed.

In assembling, it will be obvious that, sockets 13, 14 and 15 being first secured in the respective concave elements, the wired plug 13' is to be seated in socket 13 before the 105 flanges 27 and 28 of concave elements 11 and 12 are brought into mutual engagement and the hooks 42 are seated by the slight rotative movement referred to. The plate 21, gasket 25 and band 31 (or band 31a) may be separately assembled within the rim 19 (or 19a) 110 in such manner as to permit separate storage, shipment, sale and application or removal thereof as a unitary sub-assembly; and, when applied in the indicated manner, this sub-assembly may be secured in place by merely tightening the screw 36, or its equivalent.

Although the foregoing description has included specific embodiments of the present invention, it should be understood not only that various features of this invention might be independently employed but also that numerous additional modifications thereof might easily be devised by workers familiar with the foregoing,—all without the 115 slightest departure from the scope of the present invention.

I claim:

1. In a headlamp, a concave outer shell, a concave reflector therein, and a light-trans-

mitting plate, means for holding said shell, reflector and plate in mutual engagement comprising a hollow rim engaging said plate and a tension band within said rim con-
5 strictively engaging said shell and rim, additional means for positioning and securing said reflector to said shell comprising interfitting flanges thereon having a bayonet-
10 joint connection, and means to prevent relative rotation between said shell, reflector and plate comprising an element carried by said rim and interengaging between said plate and interfitting flanges.

2. In a headlamp, a concave outer shell, a concave reflector therein, and a light-trans-
15 mitting plate, means for positioning said re-
flector relative to said shell comprising in-
terfitting flanges thereon, means for hold-
ing said plate, reflector and shell in mutual
20 engagement comprising a hollow rim includ-
ing a flange engaging said plate, a contract-
ible band therein engaging said shell and
said rim with externally accessible means to
contract said band, and means for prevent-
25 ing relative rotation between said plate, re-
flector and shell comprising a notch in said
plate and openings in said interfitting
flanges, and an element on said rim extend-
ing through said notch and openings.

30 3. In a headlamp, a concave outer shell,
a reflector therein, a light-transmitting plate,
positioning means for said shell and reflector
comprising interfitting flanges thereon, and
holding means for said shell, reflector and
35 plate including a split hollow rim and a
contractible tension band therein, and means
to unite the adjacent ends of said split rim
and prevent relative rotation between said
shell, reflector and plate, comprising an ele-
40 ment connected to said adjacent rim ends
having a portion thereof engaging said plate
and said interfitting flanges on said shell
and reflector.

In testimony whereof I affix my signature.

45 ALBERT R. LEWELLEN.
